UNITED STATES PATENT OFFICE.

OSCAR L. SCHLUMPF, OF SEWICKLEY, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

SCREW DOWN FOR ROLLING MILLS.

Application filed October 17, 1924. Serial No. 744,171.

The present invention relates to screw-downs for rolling mills. It is customary to operate the two screws for adjusting the upper roll of a two-high blooming mill by power through a transverse shaft having bevel pinions on its ends meshing with bevel pinions associated with the screws. The transverse shaft has a gear mounted thereon and the pinion on one end of the shaft has a sleeve portion with a flange at one end which is bolted to the gear. The gear is located in a gear housing and is operatively connected to a motor or other source of power. When it is desired to adjust one of the screws independently of the other it is necessary to remove a portion of the gear housing and unbolt the gear from the pinion. This operation involves considerable labor and time. By the present invention I have provided means associated with one of the screws whereby its pinion can be quickly disengaged from the pinion on the end of the transverse shaft.

In the accompanying drawings:—

Figure 1 is a vertical sectional view of a screw-down for a two-high blooming mill embodying my invention.

Figure 2 is a vertical sectional view of the portion of the screw-down having my invention associated therewith,

Figure 3 is a horizontal section on the line III-III of Figure 2, and

Figures 4 and 5 are detail views of elements of the construction.

Referring to Figure 1, 2 designates a cross-head and 3 and 4 screws having their threaded portions engaging nuts 5 in the cross-head. Mounted on the cross-head are pinion housings 6 and 7 in which are journaled sleeves 8 and 9. The upper end portions of the screws 3 and 4 are unthreaded and of non-round cross-section. These upper end portions have telescopic engagement with the sleeves 8 and 9. Extending between the sleeves 8 and 9 is a horizontal drive shaft 10 having bevel pinions 11 and 12 mounted on its ends. This shaft is journaled in bearings 13 and 14 in the pinion housings 6 and 7. The bevel pinion 12 meshes with a bevel pinion 15 which is keyed to the sleeve 9, and the bevel pinion 11 meshes with a bevel pinion 16 which is keyed to the sleeve 8 but is adapted to move axially thereof and of the screw 3.

Journaled on the sleeve 8 below the bevel pinion 16 is a worm gear 17 engaged by a worm 18 on a horizontal shaft 19. This shaft is journaled in bearings in the pinion housing 6 and has a wheel 20 on one end provided with openings 21 for receiving a pin for turning the shaft, as shown in Figure 3.

Referring to Figure 5 it will be seen that the worm gear 17 has a series of integral cam elements 22 projecting from its upper face and arranged adjacent the periphery of the gear. These cam elements have inclined surfaces 23 terminating in horizontal surfaces 24. Cooperating with these cam elements is a ring 25 having inclined surfaces 26 for cooperation with the inclined surfaces 23, and horizontal surfaces 27 for cooperation with the horizontal surfaces 24. The ring 25 is interposed between the worm gear and the lower end of the pinion 16. It has a lug 28 projecting from the periphery thereof which extends into the space between two parallel vertical guide lugs 29 projecting from a wall of the pinion housing 6. It will be apparent that this construction permits the ring 25 to be raised and lowered but prevents it from turning. The worm gear 17 has a lug 30 projecting laterally from one of the cam elements 22. This lug is adapted to engage a lug 31 projecting inwardly from a wall of the pinion housing 6 to limit rotation of the worm gear in one direction. Rotation of the worm gear in the opposite direction is limited by the engagement of the vertical shoulders 32 of the cam elements 22 with the vertical shoulders 33 on the ring 25.

Figure 1 illustrates the position of the parts when the pinion 16 is elevated into mesh with the pinion 11 on the shaft 10. In this position of the parts the worm gear 17 has been rotated to a position such that the lug 30 is in engagement with the lug 31, as illustrated by the dotted line position of the lug 30 in Figure 3. Horizontal surfaces 24 of the cam elements 22 are in engagement with the horizontal surfaces 27 of the ring 25. Figures 2 and 3 illustrate the positions of the parts when the bevel pinion 16 has been lowered out of mesh with the bevel pinion 11. In this position of the parts the worm gear 17 has been rotated to bring the shoulders 32 on the cam elements

22 into engagement with the shoulders 33 on the ring 25. With the bevel pinions 11 and 16 out of mesh the shaft 10 can be rotated to adjust the screw 4 without effecting adjustment of the screw 3. The shaft 10 has a gear 34 mounted thereon arranged in a gear housing 35 and operatively connected with a motor or any other suitable source of power, as usual.

10 It will be seen that with this construction one of the screws can be very quickly disconnected from the driving connections between the two screws by simply inserting a pin in one of the openings in the wheel 20 of the shaft 19 and turning the shaft to rotate the bevel gear 17 into the position shown in Figures 2 and 3. The bevel pinions 11 and 16 can be thrown into mesh again by a reversal of this operation.

20 While I have shown and described a preferred embodiment of my invention, it will be understood that the invention is not limited to the details of construction shown and described, but may be otherwise embodied within the scope of the appended claims without departing from the spirit of the invention.

I claim:

1. In a screw-down for rolling mills, a pair of screws, a sleeve slidably keyed to the upper ends of the screws, a bevel gear on each sleeve, one of the bevel gears being slidably keyed to the sleeve on which it is carried, a transverse drive shaft having pinions thereon for engagement with the respective bevel gears, and means for raising and lowering the slidably keyed gear into and out of engagement with the driving pinion, substantially as described.

2. In a screw-down for rolling mills, a pair of screws, a sleeve slidably keyed to the upper ends of the screws, a gear carried on each sleeve, one of the gears being slidably keyed to the sleeve on which it is carried, a driving means operatively interposed between the two gears, and means for raising and lowering the slidably keyed gear into and out of engagement with the said driv-

ing means, including a fixed cam element and a movable cam element, both surrounding the screw and independent thereof, substantially as described.

3. In a screw-down for rolling mills, a pair of screws, a sleeve slidably keyed to the upper ends of the screws, a bevel gear on each sleeve, one of the bevel gears being slidably keyed to the sleeve on which it is carried, a transverse drive shaft having pinions thereon for engagement with the respective bevel gears, and cooperating cam elements movable relatively to each other for raising and lowering the slidably keyed gear into and out of engagement with its respective driving pinion, substantially as described.

4. In a screw-down for rolling mills, a pair of screws, a sleeve slidably keyed to the upper ends of the screws, a bevel gear on each sleeve, one of the bevel gears being slidably keyed to the sleeve on which it is carried, a transverse drive shaft having pinions thereon for engagement with the respective bevel gears, a non-rotatable support for the slidably keyed gear having a cam element on its lower face, a rotatable cam member under the support cooperating therewith, and means for rotating the cam member, substantially as described.

5. In a screw-down for rolling mills, a pair of screws, a sleeve slidably keyed to the upper ends of the screws, a bevel gear on each sleeve, one of the bevel gears being slidably keyed to the sleeve on which it is carried, a transverse drive shaft having pinions thereon for engagement with the respective bevel gears, a non-rotatable support for the slidably keyed gear having a cam element on its lower face, a rotatable cam member under the support cooperating therewith, and means for rotating the cam member, including a worm gear, substantially as described.

In testimony whereof I have hereunto set my hand.

OSCAR L. SCHLUMPF.
